US0D1062025S

(12) **United States Design Patent** (10) Patent No.: **US D1,062,025 S**
(45) Date of Patent: ** Feb. 11, 2025

(54) **LIGHT FIXTURE COUPLER**

(71) Applicant: **AXIS LIGHTING INC.**, Lasalle (CA)

(72) Inventors: **Howard Yaphe**, Lasalle (CA); **Andrew Miles**, Lasalle (CA); **Stéphane Béland**, Lasalle (CA); **Jean Gagné**, Lasalle (CA)

(73) Assignee: **Axis Lighting Inc.**, Lasalle (CA)

(**) Term: **15 Years**

(21) Appl. No.: **29/749,167**

(22) Filed: **Sep. 3, 2020**

Related U.S. Application Data

(60) Continuation of application No. 29/664,458, filed on Sep. 25, 2018, now Pat. No. Des. 895,888, which is a continuation of application No. 29/601,129, filed on Apr. 19, 2017, now abandoned, which is a division of (Continued)

(57) **CLAIM**

The ornamental design for a light fixture coupler, as shown and described.

DESCRIPTION

FIG. 1 is a perspective view as viewed from above of the light fixture coupler showing our design;

FIG. 2 is a perspective view as viewed from below thereof;

FIG. 3 is a top plan view thereof;

FIG. 4 is a bottom plan view thereof;

FIG. 5 is a left side elevational view thereof; and,

FIG. 6 is a right side elevational view thereof.

The broken lines in the drawings are directed to environment and are for illustrative purposes and form no part of the claimed design.
